UNITED STATES PATENT OFFICE.

JOHN HANSEN, OF BETTENDORF, IOWA, ASSIGNOR OF FOUR TWENTY-FIFTHS TO WILIAM H. MARTIN, TEN TWENTY-FIFTHS TO T. S. CUNNINGHAM, AND ONE TWENTY-FIFTH TO THOMAS McQUARRIE, ALL OF DAVENPORT, IOWA.

MECHANICAL GOLF INSTRUCTOR AND EXERCISER.

Application filed October 25, 1926. Serial No. 143,977.

My invention pertains to a mechanical golf instructor and exerciser, and is similar in character to the machine for which I have filed an application for Letters Patent of the United States under date of October 14, 1926, Serial No. 141,438. In said former device attention was paid to the fact that in the customary stroke of a golf club, as in making a drive, there is an axial movement of the stick, amounting to a half rotation in the lower part of the sweep of the club. Said device was so constructed and arranged as to offer no interference to this movement. In the present invention special mechanism is provided whereby the axial movement referred to is compulsory, the club being controlled and guided in such a manner that it will follow the desired movement. By this means a novice at the game can become accustomed to the established swing of the club in much less time than by the usual means for practice, and the more seasoned player can perfect his swing, and reduce the number of strokes which it is necessary to take in actual play.

The present invention has the same advantages as to use for indoor practice and exercise and the like which have been specified for the device set out in said prior application.

In the drawings:—

Fig. 1 shows the invention in front elevation.

Figs. 2, 3, and 4 show fragmentary sections of the rail with the traveller mechanism shown thereon in progressive positions.

Fig. 5 is a cross-section through the rail and traveller mechanism, on approximately the broken line 5—5 of Fig. 6.

Fig. 6 is a plan view of the traveller with the top of the rail broken away.

Fig. 7 is a longitudinal view of a fragmentary part of two rail sections at the joint thereof.

Fig. 8 is an end view of one of the rail sections, with the splice 11 shown in section.

The reference number 1 indicates a base or platform, suitable for the support of a person that is making use of the machine, from one side of which platform is erected a frame 2, the side-pieces of which are united

by cross-pieces 3 and 4, and the lower part of the frame is further secured by braces 5. Mounted on the other side of the base from the frame 2 is a rail of oval formation constructed of sectional arcuate pieces 6, 7, 8, 9, and 10. The upper part of said rail is attached to the frame 2, the rail and frame being inclined toward each other and meeting at a point above the base. The end sections 6 and 10 overlap each other, and the general conformation of the rail is the same as that of the movement of the head of a golf club in making a stroke. At the joints of the several rail sections are splice plates 11 on the inner face of the rail, said plates being of channel-plate formation, and held in place by bolts 12. Pins 13 fixed in the rail sections enter openings in the splice plates and relieve the bolts from lateral strain. The ends of the sections are also provided with pairs of pins 14, which prevent such ends from getting out of alignment.

A traveller is provided for movement along the inner edge of the rail, consisting of a rectangular frame 15, in the corners of which are pins 16 and 17 upon which are mounted rollers 18, provided with anti-friction bearings, and operable in channels 19 in opposite faces of the rail, near the inner edge thereof. The peripheries of said rollers are preferably of an arcuate formation, as shown, and the channels are of a corresponding formation, whereby the surface friction between the roller and rail is reduced to a minimum.

Fixed to the upper end of the pin 17 is a swivel coupling 20, one part of which is adapted for attachment to the head 21 of a golf stick 22, such stick being of suitable length for use by a person standing on the base 1, at a central point of the rail. Projected downwardly from the frame 15 on the outer side of the rail is a bracket 23, in the lower end of which is journalled a shaft 24, to the inner end of which is fixed a bevel segment gear 25, in mesh with a bevel gear pinion 26 fixed to the lower end of the pin 17. A gear pinion 27 is also fixed on the shaft 24, adapted for rotation by a segment gear rack 28 on one end of an arm 29, fulcrumed on the lower end of a bracket 30 supported from the frame 15, as at *a*. The other

end of the arm 29 is provided with a roller 31, operating in a track 32, in the outer face of the rail. Supported from the base 1 is a frame 33, serving as a support for a golf ball shown at 34, in the path of the head 21 of the golf club.

In the operation of the machine the player stands on the base 1 as before stated, with the stick 22 held in approved manner, the stick being then carried upwardly until the traveller 15 is at the upper end of the section 6 of the rail. The stick is then swung downwardly to the lower part of the rail and then upwardly again, following the usual stroke 15 of a golf club, finishing at the end of the section 10. On the section 6 of the rail the track 32 is near the inner edge thereof, adjacent to the channel 19, but at a point at the player's right said track is carried gradually outwardly, until at a point at the left of the player said track is at the outer edge of the rail, as shown on section 9, and continues in that position to the outer end of the section 10. In the first-named position the 25 arm 29 is held with the segment 28 turned outwardly, as shown in Fig. 2, which results in the pinion 26 and coupling 20 being turned to bring the club into position with the face thereof toward the front, as shown in Fig. 1. This is the natural position of the club for the first part of the stroke. As the traveller approaches the lower part of the rail the rack 28 is moved into a neutral position, as shown in Fig. 3, in which position the face of the 30 head 21 of the club is toward the ball, as in Fig. 5. As the traveller is brought upwardly again at the left of the player the track 32 carries the roller 31 gradually outwardly, turning the rack 28 inwardly, as shown in Fig. 4, the consequent movement of the segment 25 and pin 17 turning the stick 22 until the face of the head 21 is to the rear, in which position it continues for the 35 balance of the stroke. As a result the golf club is not only compelled to follow the usual course for a perfect stroke, but the stick is turned automatically into the prescribed positions for accompanying such stroke. The beginner soon becomes accustomed to the 40 movement, and will follow it naturally, without the use of the machine. The more seasoned player will be able to improve and perfect the style of his swing, and reduce the number of strokes required in actual 45 practice.

In carrying the club backwardly again to the starting point the rotary movement of the stick will be reversed, until the face of the head is again toward the front for the 50 initial part of the stroke.

The guiding mechanism for the stick, as shown in the drawings, is greatly out of proportions, such mechanism being of comparatively small and light construction, so as to offer little resistance to the movement

of the stick. By reason of the rail being formed in sections, as set forth, it can be readily taken apart for transportation.

What I claim, and desire to secure by Letters Patent, is:

1. A device of the class described, comprising a rail and support therefor, a traveller movable along said rail, and adapted for connection with the head end of a golf club, and mechanism associated with said traveller for giving a gradual rotation to the stick of a golf club connected therewith during the movement of said traveller along the rail, conforming to the usual movement of the stick in making a stroke. 70

2. A device of the class described, comprising a suitably mounted rail of eccentric formation, conforming to the movement of a golf club head in making a customary stroke, a stick guiding mechanism slidable along said rail and provided with a swivel coupling for connection with the head end of a stick, and means for imparting a rotary movement to said coupling during a portion of the movement of said guiding mechanism 80 corresponding with the rotary movement of the stick of a golf club in making a stroke. 85

3. A device of the class described, comprising a suitably mounted rail conforming in shape to the movement of a golf club 90 head in making a customary stroke, a traveller movable along said rail, provided with means for connection with the end of a stick permitting an axial rotation of said stick, a cam track in said rail, and a follower for 95 said cam track operatively connected with said stick connecting means so as to impart a desired rotation to a stick connected therewith during a portion of the movement of the traveller along said rail. 100

4. In combination with a rail and traveller movable thereon, a coupling device carried by the traveller, capable of a pivotal rotation, a stick connected with said coupling device, and axially rotatable thereby, gearing operatively connected with said coupling device, and means carried by said rail for actuating said gearing to give a desired rotary movement to said stick in making a stroke. 105

5. In combination with a suitably mounted rail and cam track thereon, a traveller movable along said rail, a pivotal member in said traveller adapted for connection with the end of a golf club, gearing connected 110 with said pivotal member capable of imparting rotation thereto, a follower for said cam track also carried by said traveller, and gearing operatively connecting said follower with said first-named gearing, and actuating 115 the same during a portion of the movement of said traveller along said rail.

6. In a device of the class described, a suitably mounted rail conforming in shape 120 to the usual movement of the head of a golf 130

club in making a drive, and provided with a cam device on one of its faces, a frame provided with friction reducing mechanism bearing on opposite sides of said rail, a connecting means carried by said frame for the attachment of the end of a golf stick thereto, permitting axial rotation of such stick, gearing operatively connected with said stick connecting means, and means connected with said gearing for engagement with said cam device, to give a partial axial rotation to a stick connected with said frame during a partial movement of the frame along said rail. 10

In testimony whereof I affix my signature.
JOHN HANSEN.
